UNITED STATES PATENT OFFICE.

NILS SEAHOLM, OF MOUNT VERNON, NEW YORK.

SOUND MODULATOR FOR PHONOGRAHS.

1,414,673.

Specification of Letters Patent. Patented May 2, 1922.

Application filed December 24, 1920. Serial No. 432,994.

To all whom it may concern:

Be it known that I, NILS SEAHOLM, a citizen of the United States, and a resident of the city of Mount Vernon, in the county 5 of Westchester and State of New York, have invented certain new and useful Improvements in Sound Modulators for Phonographs, of which the following is a specification.

10 This invention relates to a modulator or sound modifier for graphophones or phonographs and the like. It more particularly appertains to a device interposed between the stylus of a sound reproducing machine 15 and the sound box thereof by means of which the audibility of the acoustic waves may be regulated.

One of the objects of the invention is to provide a device of the character described 20 which is applicable to different makes of phonographs now in use and capable of accommodating various types of needles for the same.

Another object is to produce a device of 25 the nature set forth whereby the reproduction of sound from a record can be rendered in any desired degree of softness and without muffling it, at such times when it is desirable to keep the sound from reaching adjoining rooms.

A further object is the production of a 30 device of the type specified wherein the weight of the sound box is resiliently carried and irregularities occurring in the various movements between the stylus and the record are compensated in order to obviate excessive wear upon the latter.

Still another object is the provision of a 35 device of the class mentioned enabling the intensity of the sound to be regulated in proportion to an interposed resistance, while the record is being played.

A still further object in producing a device of the species referred to, is the embodiment of means for adjusting the angular inclination of the stylus relatively to the sound grooves in accordance with the audibility desired but without altering the leverage of the stylus or changing the position thereof within its holding socket.

An additional object is to supply a device of the genus alluded to composed of few, simple and durable parts, quickly and easily assembled and of low manufacturing 55 cost, not liable to get out of order, and

which may be readily installed as well as operated by the average person.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same reference characters throughout the several views.

In the said drawings:—

Figure I is a side elevation showing this improved device in operative position with respect to a sound box and a record of a phonograph of well known type;

Figure II is an enlarged sectional elevation of the device alone, in a position conducive to the maximum softening of the sound.

Figure III is a top plan view of the device shown in the preceding figure;

Figure IV is a view similar to Fig. II, showing the device in a position corresponding to a minimum of tone suppression; and

Figure V is a rear elevation of the device in the position seen in the last named view.

Generally described, the invention includes in its organization a pair of spaced, hingedly connected members. From one of the latter extends a shank adapted for insertion into the needle socket of a phonograph, while the other one of its members affords a socket capable of receiving an ordinary stylus. Differentially acting resilient elements interposed between these members tend to maintain them in normal position. A means is provided for varying the interrelative rigidity of the elements and thereby change the amplitude of the sound transmitted from the stylus to the sound box through the members, adjustment of the same being limited by stops forming with the means above mentioned a continuous path for the sound waves.

The advantages of the invention as here outlined are best realized when all of its features and instrumentalities are combined in the one and same structure, but useful devices may be produced embodying less than the whole.

It will be obvious to those skilled in the

art to which the invention appertains, upon becoming conversant with the details thereof, that the same may be incorporated in several different constructions. The accompanying drawing, therefore, is submitted merely as showing the preferred exemplification of the invention.

Referring now to the several views of the drawing for a detailed description of the invention and in which the known elements of a sound reproducing machine have been indicated in dot-and-dash lines, the reference letter A denotes a sound box carried from a sound arm B and having a vibratory diaphragm C. D designates a vibrating lever fastened at one end to the diaphragm C and having at its opposite extremity a socket E ordinarily adapted to receive a stylus. This lever is fulcrumed intermediate of its ends to the sound box A as at F. G is a thumb-screw for holding the shank of the stylus in the socket E. A record H of the flat disc variety is shown supported by a turn table J which is rotatable over a cabinet K.

11 designates a relatively fixed member to which a companion member 12 is movably connected, as for example, by a hinge pin 14 pivotally coupling opposed inwardly facing ears 15 and 16 wherewith the members 11 and 12 are provided. Near or at the corresponding ends of the members 11 and 12 are outwardly projecting portions or lugs 19, 20. From the first named lug 19 extends a shank 21 in substantial parallelism with the member 11 and adapted for insertion into the socket E of the lever D.

In the lug 20 is a socket 22 substantially parallel with the member 12 adapted for the reception of a stylus or needle L which is held in place therein by a thumb-screw 23 operable by means of a knurled head 24 or otherwise as may be desired. The socket 22 therefore serves the purpose for which the socket E was designed.

As indicated in Figs. I and II, the members 11 and 12 are maintained in normal position by one or more resilient elements 26 and 27 which, as shown, may be helical compression springs located at different distances from the pivot or fulcrum point 14. The spring 26, which is at a greater distance from this fulcrum and therefore acts with a longer leverage may preferably have coils of smaller size and of lighter wire than the spring 27, the latter being of heavier wire wound into coils of a slightly larger diameter and is for that reason the stronger. But, as the same is placed nearer the pivotal point 14 it exerts a resistance equal to 26 thus serving to balance the latter and to maintain the members 11 and 12 normally in equipoise.

This arrangement of differentially acting spring elements has been found in practice

to give the best results in transmission of sound in a device of this character.

As will be apparent from Figs. II and IV, the elements 26, 27 have their opposite terminals received within recesses or cavities 28, 29 and 30, 31 in the members 11, 12. The first named recess 28 which is the deepest for the reception of the spring 26 is formed in the lug 19 of the member 11.

To differentiate the action of the springs 26, 27, a thumb-screw 33 having an easily manipulated head 34 is provided. This screw is threaded into the lug 19 and located so as to exert an endwise thrust upon the corresponding terminal of the spring 26 when driven into the recess 28. The further the screw 33 is forced against the spring element 26, the greater will be the pressure applied on the element 27 as well, and the more rigidity put on to the members 11 and 12. In other words, the less becomes the interrelative flexibility between the members 11 and 12 and the stronger are the sound waves passing through the structure.

In view of the longer leverage of the spring 26 the sidewise flexure thereon is minimized when the members 11 and 12 are forced into the convergent position represented by Figs. IV and V. By reason of the fact that this spring 26 is disposed in close proximity to and in direct alignment above the stylus L, any backlash occurring between the parts is taken care of, this being conducive to a constant transmission of the sound.

Moreover, owing to the rearwardly offset disposition of this attachment, the overhang thereof is reduced to a minimum while the position of the stylus L and its inclination is kept as nearly as possible the same with respect to a line passing vertically through the center of the sound box A as when the stylus L is inserted directly into the socket E of the sound lever D.

In order to limit the convergency between the members 11 and 12 suitable stops are provided. The same comprise preferably, headed pins 35, 36, having their shank portions passing through the springs 26, 27 respectively, while their heads overlie the springs on one end.

As shown in Fig. II the point of the screw 33 abuts directly against the head of pin 35, and in the innermost position of the said screw, the headless end of the pin 35 is pressed to the bottom of the recess 29. At the same time as this occurs both ends of the pin 36 are forced against the bottom of their respective recesses, being squeezed between the shorter lever arms of the members 11, 12 which are thereby precluded from further movement.

In this last position the members 11, 12 are obviously relatively immovable, being held from partaking of independent oscilla-

tory motion. The resilient elements 26, 27, have then been temporarily shunted out as sound conductors. The means which resiliently couple the said members, comprise 5 the pivot 14 and the oppositely acting spring elements 26, 27, while the other means that rigidly connect these members consist of the screw 33 pressing thereon together with the pins 35, 36.

10 Auxiliary means are provided for adding graduated increase of resistance to that of the springs 26, 27 against tilting of the members 11 and 12. This latter means is arranged to act shortly in advance of the members 11 and 12 being locked together. To this end a pair of L-shaped springs have their toe portions 38, 39 inserted into an aperture provided therefor in the member 12 slightly beyond the pivot 14 on the 15 shorter leg of the member 11. Legs 40, 41 of these supplementary spring elements are offset with respect to each other, but the ends thereof are brought up against a common stop 42 which may consist of a pin driven 20 into the member 11 in proximity to the lug 19.

The construction is such that first one of the legs 41 is brought into contact with the stop 42 at one side of the member 11 and if 25 the oscillatory movement of the member 12 is continued, the other leg 40 is subsequently forced against the pin 42 at the opposite side of the member 11. In this way the graduated resistance mentioned above is obtained 30 prior to the members 11 and 12 reaching their deadlocked position.

Preferably the ears 15, 16 are provided at the opposite faces with hub portions 43, 44 which are suitably grooved or channelled to 40 receive the legs 40, 41 of the said springs. Washers 45, 46 overlie the grooves that receive the middle parts of the legs of the auxiliary springs and serve to keep the latter in their assigned positions. The extremities 45 of the pin 14 which pass through the said washers are headed or upset to retain them from displacement.

From the foregoing it will be observed that the working parts of the device are disposed and operate in the same plane as the 50 original stylus socket E which also coincides with the altered or new position of the stylus D itself. This arrangement of parts insures a balanced action of the device.

55 The contact point of the stylus with the record H is beyond the pivotal connection 14 and all irregularities or minute but multitudinous impacts produced by the record upon the stylus are compensated or absorbed 60 by the springs 26, 27, so that only a clear sound free from discordance is transmitted.

There is nothing to be tampered with or 65 get out of order. The mere adjustment of a single screw 33 will either increase or decrease the inclination of the styles to soften

or strengthen the sound as may be required.

While a certain preferred embodiment of this device has been shown and described, it will be understood that changes in the form, arrangements, proportions, sizes and details 70 thereof may be made, without departing from the scope of the invention as defined by the claims.

Having described my invention what I desire to secure by Letters Patent and claim, 75 is:

1. In a sound modulator for phonographs, the combination with the sound box and vibrating lever of the latter, of an attachment comprising a member carried by said lever, another member yieldably connected thereto adapted to receive a stylus, and means for varying the interrelative rigidity between said members. 80

2. In a sound modulating device for 85 phonographs and the like, the combination with the sound box and vibratory lever of the latter, of an attachment comprising a member having a part adapted to engage said lever, another member flexibly connected with said first named member and provided with a portion capable of receiving a sound reproducing needle, and means adjustable for varying degrees of resiliency 90 coacting with said members. 95

3. In a sound modulator for phonographs, the combination with the sound box and vibrating lever of the latter, of a device comprising a pair of flexibly coacting pivoted members, one of said members being 100 adapted for connection with said lever, while the other one thereof is capable of receiving a sound reproducing needle, and means for varying the flexibility of action between the said members. 105

4. In a sound modulator for phonographs and the like, the combination with the sound box and vibratory lever of the latter, of a device comprising a pair of flexibly coacting members, one of said members being carried 110 by said lever, while the other one thereof is adapted to receive a stylus, differentially acting means connected up with the said members, and other means for varying the action of said first named means. 115

5. In a sound modulator for phonographs and the like, the combination with the sound box and vibrator lever of the latter, of a device including flexibly joined members one of which is carried by said lever while 120 another one thereof is adapted to hold a stylus, means for resiliently coupling said members, and other means for rigidly connecting the same.

6. In a sound modulator for phonographs 125 and the like, the combination with the sound box and vibratory lever of the latter, of a device including a pair of flexibly coupled members supported from said lever, one of said members being adapted to hold a sty- 130

lus, a resilient element connected up with the members, and means for varying the resiliency of said element whereby the transmission of sound waves between the members may be controlled.

7. In a sound modulator for phonographs and the like, the combination with the sound box and vibrating lever for the same, of a device comprising a pair of flexibly joined members supported from said lever, a stop on one of said members, one of said members being adapted to hold a stylus and carrying means to engage said stop, a resilient element connected up with the said members, and adjustable means for varying the resiliency of said element capable of bringing the members into rigid relation with each other by contact of said first named means with the stop.

10 8. In a sound modulator for phonographs or the like, the combination with the sound box and vibrating lever for the same, of a device comprising a pair of flexibly joined members supported from said lever, one of which is adapted to hold a stylus, a stop on one of said members, a resilient element carried by the other member capable of offering resistance to the movement of the members by engaging said stop, a spring interposed between the said members, and screw means for diminishing the distance between the members against the resistance of said spring and said resilient element.

15 9. In a sound modulator for phonographs, the combination with the sound box and its vibratory lever, of a device comprising a pair of pivotally connected members supported from said lever, one of said members being adapted to receive a stylus, differentially acting resilient elements coupled up with the said members maintaining them in normalcy, and adjustable means for varying the resiliency of said elements to control the transmission of sound therethrough.

20 10. In a sound modulator for phonographs, the combination with the sound box and its vibratory lever, of a device comprising pivotally connected members supported from said lever, one of said members being adapted to hold a stylus, differentially acting resilient elements intermediate of the said members maintaining them in normal position, stops coacting with the latter, and means for adjusting the resiliency of said elements to vary the interrelative flexibility between the members, said means being capable also of forcing the latter into rigid contact with said stops.

25 11. A device of the character described comprising in combination, a member having a shank adapted to be inserted into the stylus socket of a phonograph, another member capable of receiving a sound reproducing needle pivotally connected to said

first named member, resilient elements interposed between corresponding ends of the said members, the same being formed with recesses for the reception of said elements, stops intermediate of said ends, and a screw entering one of said recesses arranged primarily to vary the compression upon said elements thereby controlling the members' interrelative flexibility, and subsequently forcing the latter into locking position with said stops.

30 12. A device of the character described comprising in combination, a member having a shank designed for insertion into the stylus socket of a phonograph, another member capable of receiving a sound reproducing needle pivotally connected to said first named member, the corresponding ends of said members having recesses therein, resilient elements interposed between said ends and resting in said recesses, a screw entering one of the latter adapted to vary the resistance of the resilient element therein and to lock the said members together, stops on one of the members, and auxiliary means on the other member co-operating with said stops to increase the resistance between the members just prior to their becoming locked.

35 13. A device of the character described comprising in combination, a pair of pivotally connected members, one of them having a shank arranged for insertion into the needle socket of a phonograph, while the other one is adapted to receive a stylus, springs of varied strength interposed between said members at different distances from their pivotal connection, stops mounted in said springs intermediately of the said members, and a screw carried by one of the latter capable of regulating the action of the 40 springs to control the members' interrelative flexibility, and to force the same in rigid engagement with said stops.

45 14. A device of the character described comprising in combination, a pair of pivotally connected members, one of them having a shank arranged for insertion into the needle socket of a phonograph, while the other one is adapted to receive a stylus, springs of varied strength interposed between said members at different distances from their pivotal connection, stops mounted in said springs intermediately of the said members, a screw carried by one of the latter capable of regulating the interrelative 50 action of the springs and the members and to bring the same into locking engagement with said stops, and an auxiliary spring supported by one member in abutting relation to the other affording a gradually increasing resistance prior to the members becoming locked.

NILS SEAHOLM.
